United States Patent Office.

ALPHONZO BUTTON, OF DUNKIRK, NEW YORK, ASSIGNOR TO MATSON O. WILBER, FOR ONE-HALF OF SAID PATENT.

Letters Patent No. 98,145, dated December 21, 1869.

IMPROVEMENT IN POCKET-BOOKS.

The Schedule referred to in these Letters Patent and making part of the same.

To all whom it may concern:

Be it known that I, ALPHONZO BUTTON, of Dunkirk, in the county of Chautauqua, and State of New York, have invented a new and improved Note-Case; and I do hereby declare that the following is a full, clear, and exact description thereof, which will enable others skilled in the art to make and use the same, reference being had to the accompanying drawings, forming part of this specification.

This invention relates to improvements in note or paper-cases, or files for enclosing notes, papers, bills, &c., in a simple, cheap, and convenient portable package, for the use of bankers and other business-men.

It consists of a cylindrical case, of leather or other light suitable material, having an opening from end to end, covered by a flap, a central revolving spool, and a web of flexible substance, connected to and wound on the spool, so as to be drawn out through the opening and wound up again, on which web any suitable arrangement of narrow flaps, folding over from the edges, and connected by elastic bands in a way to secure papers, notes, &c., in different and separate sections, may be arranged, as now arranged in pocket-books.

Figure 1 represents a plan view, partly broken out, of my improved case, the note-holding sheet being partly drawn out, and

Figure 2 represents the case in the closed condition.

Similar letters of reference indicate corresponding parts.

A is the cylindrical case, consisting of a cylinder of leather or thin sheet-metal, covered with thin, light leather or other suitable substance, and closed at the ends by wood or other heads B.

This case has a long and narrow opening extending from end to end, and a flap, C, of the leather or other covering, lapping over the same; and this flap is provided with elastic bands D, connected by passing

through holes near the edges of the flap, or in any other suitable way, so as to stretch over the ends and contract around the cylinder, to hold the flap in the closed condition.

E is a spool, the shaft of which is journaled in the heads B at their axes, and one end projects through its head, and is provided with a thumb-knob for turning it.

F is a web or sheet of canvas, leather, or other suitable substance, attached at one end to the spool, the other being arranged to project through the slot, so as to be drawn in and out by winding on or off the spool.

This sheet F is provided at the sides with flaps G, folding over upon the upper side, and connected together by elastic bands H, for holding papers, notes, and the like, in different packages, which, after being placed on and secured to the same, may be drawn in and rolled around the spindle of the spool in a compact way, the whole constituting a convenient package for carrying in the hand.

They may be made in any suitable sizes for the various different uses to which they may be applied.

For protecting the edges of the case, at the openings, from damage by the action of the sheet F in drawing out and in, I arrange wires I in front of the said edges, and, to facilitate the moving of the sheet F over the said wires, they may have loose tubes upon them to act as friction-rollers.

Having thus described my invention,

I claim as new, and desire to secure by Letters Patent—

The combination of the slotted cylindrical case A, spool E, and note and paper-holding sheet F, substantially as specified.

ALPHONZO BUTTON.
